ADJUSTABLE CHILD'S SEAT

William F. Kelley, Roxbury, Conn.

Application March 24, 1948, Serial No. 16,752

2 Claims. (Cl. 155—88)

1

This invention relates to furniture, and more particularly to a child's seat adapted to be placed upon an adult's chair, bench, or other horizontal surface, so as to increase the effective height thereof.

One object of this invention is to provide a seat of the above nature which includes means for adjusting its height, whereby the seat may be used to support children or other persons of different sizes at the desired level upon an adult's chair for use at the dining table, the theater, or other places.

Another object is to provide a device of the above nature in which the adjusting means comprises a plurality of interfitting and interchangeable blocks adapted to be inserted between the top and base of the seat.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawings,

Fig. 1 is a plan view of the improved child's seat.

Fig. 2 is a front elevation looking rearwardly from the line 2—2 of Fig. 1—the seat member being shown in its lowest adjusted position.

Fig. 3 is a side elevation of the same, looking to the left from the line 3—3 of Fig. 1.

Fig. 4 is a front elevation similar to Fig. 2, but showing the seat member adjusted to a higher position.

Fig. 5 is a side elevation of the same, with the top seat member disengaged to show the shape of the end slots in the insert block.

Fig. 6 is a perspective view of the end of one of the insert blocks.

Fig. 7 is a perspective view showing the child's seat as it would appear when in position upon a chair.

Referring now to the drawings in which like reference numerals denote corresponding parts throughout the several views, the numeral 10 indicates a flat base member of generally rectangular outline with rounded corners, and having a pair of elongated rectangular support blocks 11, 12 on its upper surface adjacent its opposite side edges. The support blocks 11, 12 are secured to the base member 10 by a plurality

2

of headed nails 13 each of which has a scratch-preventing rubber button 14 secured to the nail-head and located under the base member 10.

Provision is also made of a top seat member 15 having the same size and outline as the base member 10 and provided with a pair of depending rectangular side strips 16, 17 which are secured to its undersurface by means of screws 18. The upper surface of the seat member 15 preferably has a rounded concavity 19 to enhance the comfort of the child using the seat.

The side strips 16, 17 are each provided on both ends with pairs of spring clips 20, 21 whereby said side strips 16, 17 may be releasably secured to the support blocks 11, 12 of the base member 10 in order to hold the seat member 15 in assembled relation with the base member 10.

Each of the spring clips 20, 21 is preferably formed from sheet metal and comprises a flat base portion 22 which is secured to the lower surface of one of the strips 16, 17 by means of screws 23. Each clip 20, 21 also has a pair of depending side ears 24 at opposite sides of the base portion 22 and a resilient end tongue portion 25 which is bent downwardly and inwardly, as shown.

The end surfaces of the support blocks 11, 12 are each provided with a V-shaped slot 26 which forms an inclined surface adapted to be engaged by one of the resilient tongues 25.

Thus, it will be seen that the seat member 15 will normally be retained upon the base member 10, and the resilient characteristics of the tongues 25 will permit the member 15 to be readily disengaged from the base member 10 whenever desired.

A plurality of spare insert blocks 27, 28, 29, 30 are provided for the purpose of adjusting the height of the seat. The end surfaces of the insert blocks 27, 28, 29, 30 are provided with V-shaped end slots 31 which have the same shape as the end slots 26 in the support block 11, 12. A plurality of spring clips 32, which have the same form as the spring clips 20, 21, are secured one at each end of the lower surfaces of each of the spare insert blocks 27, 28, 29, 30. It will thus be seen that any desired number of the spare insert blocks may be inserted and engaged between the support blocks 11, 12 and the side strips 16, 17 in order to bring the seat member 15 to the required elevation. When used in this manner, the spring clips 20, 21, 32 will cooperate with the V-shaped end slots 26, 31 in the underlying blocks to hold the parts together.

At the same time, the side ears 24 of the clips 20, 21, 32 will prevent the blocks from becoming displaced laterally.

It will be noted by reference to Fig. 2 that when the side strips 16, 17 of the top section 15 are assembled directly with the support blocks 11, 12 of the base member 10, a storage space 33 will be provided between said top section and base member which is of a suitable size to detachably contain the spare insert blocks 27, 28, 29, 30.

In order to secure these spare insert blocks in the space 33, provision is made of a pair of insert holding rails 34 which are adapted to frictionally receive the resilient flanges 25 of the spring clips 32. The insert-holding rails 34 include flat horizontal mounting flanges 35 which are secured to the upper surface of the base member 10 adjacent the support blocks 11, 12 by means of screws 36.

It will be understood that the seat may be made of any suitable material, such as wood, metal, plastic, or fiber.

Operation

In operation, the seat may be placed upon a chair C, as shown in Fig. 7, so that a child sitting upon it will be elevated suitably at the dining table or other location. If the child is very small it will be necessary to support him at a higher level, in which case the spare insert blocks 27, 28, 29, 30 may be used in order to raise the level of the seat member 15, as shown in Fig. 4.

As the child grows older, one or more pairs of the insert blocks may be removed, so that a seat of the proper height for the child will always be available.

One advantage of the improved child's seat is that it will do away with the necessity for a special high chair.

A further advantage is that the seat may be placed upon any conventional household chair, and inasmuch as it is very compact, it will occupy less space than would be required for a special chair.

Another advantage is that the seat is entirely self-contained, and when the insert blocks are not required, they may be stored within the seat itself.

Another advantage is that the seat will avoid the old expedient of using books, pillows, etc. in order to raise the effective height of a chair so that it may be used by a child.

A further advantage is that the adjustable seat is easily portable, so that it may be carried to any

desired location for use. Thus, the seat is not limited to use at the dining table, but may be taken to theaters, ball games, and other places where it may be used by a child to raise his eye level to such a point that he can see as well as other spectators.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an adjustable seat, a base member, a pair of elongated horizontal support block elements fixed in spaced parallel relationship to the top thereof, a top seat member, and leaf spring clip means attached to the underside of said top seat member and engaged with holding means in the ends of said support block elements for detachably holding said base member and said top seat member interengaged.

2. The invention as defined in claim 1 wherein each of said leaf spring clip means comprises a horizontal base portion, a downwardly and inwardly directed tongue portion and vertical ears depending from the sides of the base portion for embracing the sides of said block elements, the holding means in said block elements being end notches receiving said tongue portions.

WILLIAM F. KELLEY.
